UNITED STATES PATENT OFFICE.

WILLIAM W. BROWER, OF NEW YORK, N. Y.

STIRRUP.

SPECIFICATION forming part of Letters Patent No. 223,577, dated January 13, 1880.

Application filed November 7, 1879.

To all whom it may concern:

Be it known that I, WILLIAM WALLACE BROWER, of the city, county, and State of New York, have invented a new and useful Improvement in Stirrups, which improvement is fully set forth in the following specification, reference being had to the accompanying drawings, in which—

Figure 1 shows a stirrup, partly in section, embodying my invention. Fig. 2 is a cross-section thereof. Fig. 3 is an inverted plan view of the same.

Similar letters indicate corresponding parts. My invention relates to elastic foot-pads for stirrups, designed to provide a yielding and adhesive surface to the foot of the rider.

My invention consists in an improved article of manufacture composed of an india-rubber stirrup-pad provided with flexible metallic strips arranged to clasp the pad to the base or foot-rest of the stirrup, as will be fully hereinafter described.

In the drawings, the letter A designates a stirrup having combined therewith a foot-pad, B, made of india-rubber. The stirrup A is of ordinary form, and the pad B is applied to its cross-bar, the whole area of which it covers, so that the surface presented to the foot of the rider is one of india-rubber throughout, and,

owing to the natural elasticity and adhesiveness of this material, the pad is a check to the slipping of the foot in the stirrup. In order to increase the effect of the pad B, I roughen the top or bearing surface thereof, as shown in Fig. 2.

The letter C designates flexible metallic straps, whereby the pad B is attached to the stirrup, these straps being secured to the pad by rivets d or other suitable means, and being bent around the cross-bar of the stirrup, as shown.

At the end of the pad B are notches e, to receive the side bars of the stirrup, and thereby to assist in holding the pad in place.

What I claim as new, and desire to secure by Letters Patent, is—

An improved article of manufacture, an india-rubber stirrup-pad provided with flexible metallic strips arranged substantially as described, and adapted to be used in securing the pad to the stirrup, as set forth.

In testimony that I claim the foregoing I have hereunto set my hand and seal this 2d day of November, 1879.

W. W. BROWER. [L. S.]
